ANTITUSSIVE COMPOSITIONS

Nathan Weiner, Rego Park, N.Y., assignor to Endo Laboratories, Inc., Richmond Hill, N.Y., a corporation of New York

No Drawing. Filed May 11, 1960, Ser. No. 28,247

13 Claims. (Cl. 167—55)

This invention relates to antitussive pharmaceutical products. In particular, it is directed to an improvement in antitussive pharmaceutical product for effecting control of coughing.

It is known that antitussive drugs act by suppression of the cough reflex. However, the known antitussives produce an undesirable collateral action. They frequently cause spasms of the smooth muscle and inhibit normal secretory mechanisms. Such actions frequently defeat the purpose for which an antitussive drug is administered, namely, to suppress a frequent and irritating cough without suppressing bronchial stimulation and liquefaction of mucus which will accumulate in the lungs.

Muscular spasm, particularly in the bronchial musculature, prevents the sufferer of a cough from eliminating viscous secretions which accumulate under those pathological conditions, in consequence of the adverse effect on the cough reflex which assists in the expulsion of such mucous plugs.

In general, the usual type of antispasmodic which relaxes the spasm of smooth skeletal muscle is not effective in relieving the spasm of the bronchial tree.

I have unexpectedly found that a particular type of antispasmodic can relieve spasms brought about by such antitussives. This particular type of antispasmodic is especially effective in combination with antitussive drugs which do not belong to the class of opium derivatives, and are non-addicting on continued use. The mentioned antispasmodics are members of the class of compounds which are synthetic esters of tropine and quaternized salts of such esters.

I have found that this particular class of antispasmodics when combined with the mentioned non-narcotic antitussives, produces an antitussive action which is superior to that of the antitussive per se, and prevents the undesirable and discomforting side actions, named above, of the antitussive.

Accordingly, it is among the principal objects of this invention to provide novel compositions having superior antitussive properties.

Another object is to provide a composition which produces antitussive action without the concomitant undesirable side effects ordinarily attending the action of antitussives.

A still further object is to provide compositions which are combinations of antitussives and a particular type of antispasmodic.

An even further object is to provide compositions which are combinations of antitussives and non-addicting antispasmodics, said antispasmodics being synthetic esters of tropine and quaternized salts thereof.

The following are examples and preferred embodiments in accordance with this invention:

Example 1

20 parts of dextro-3-methoxy-N-methyl morphinan hydrobromide is mixed with one part of homatropine methylbromide by weight. This mixture is added to a syrup containing 25 parts of pyrilamine maleate in a syrup base, containing sucrose and sorbitol and flavors, at such a concentration that in each 5 cc. there is 10 mgs. of dextro-3-methoxy-N-methyl morphinan hydrobromide and 0.5 mg. of homatropine methylbromide. This composition pro-

2

duces a rapid relief of the cough reflex in persons who suffer from a cough due to the symptoms of the "common cold." The person is also relieved from the unpleasant constipating action and "tightness of the chest" which are concurrent symptoms of the common cold.

Example 2

A tablet granulation is prepared with the following ingredients:

		Grams
10	Dextro-3-methoxy-N-methyl morphinan hydrobromide	150
	Homatropine methylbromide	20
15	Lactose	1,420
	Starch	350
	Sucrose	70
	Magnesium stearate	10

The powders are ground and mixed and converted into a granulation by the usual techniques known to the art for the manufacture of compressed tablets. The tablets are then compressed at such a diameter and gauge that the final weight of the compressed tablet is 0.202 gm. per tablet; each tablet containing 15 mg. of the antitussive ingredient (dextro-3-methoxy-N-methyl morphinan hydrobromide) and 2 mg. of homatropine methylbromide.

These tablets are applicable to the treatment of the symptoms of a cold, namely cough and "tightness of the chest," as described in Example 1.

Example 3

A granulation is prepared as in Example 2, except that 40 grams of dipropyl acetyl tropinium methylbromide is substituted for the homatropine methylbromide. The granulation thus prepared will provide 100,000 tablets weighing 0.204 gram and containing 15 mg. of dextro-3-methoxy-N-methyl morphinan hydrobromide and 4 mg. of dipropyl acetyl tropinium methylbromide. These tablets are used for the treatment of coughs due to colds, as in Example 2.

Example 4

A syrup is prepared with the following ingredients:

45	Noscapine base	grams	2
	Citric acid	do	5
50	Homatropine methylbromide	do	0.2
	Ammonium chloride	do	16
	Flavoring oils	ml.	30
	Water	ml.	10
55	Sugar syrup, U.S.P., q.s.	1,000 ml.	

The syrup contains, in each teaspoonful, 10 mg. of the non-narcotic antitussive agent, noscapine, and 1 mg. of the antispasmodic agent, homatropine methylbromide. This syrup produces excellent relief of the cough reflex, which is stimulated by the irritation of the symptoms of the common cold. However, the "tightness of the chest" and constipation, which are concomitant symptoms of this disease, are likewise relieved.

Example 5

In a fashion similar to Example 2, tablets are prepared, each containing 15 mg. of noscapine and 2 mg. of homatropine methylbromide. These tablets are used in a manner similar to the use of the syrup of Example 4, with the same symptomatic relief therein described.

Example 6

In a fashion similar to Example 3, tablets are prepared which contain, per tablet, 15 mg. of the non-narcotic antitussive, noscapine, and 5 mg. of the synthetic spasmolytic agent, dipropyl acetyl tropinium methylbromide.

When used for the relief of cough due to colds, as the

preparation of Example 3, they effectively suppress the cough and relieve the concomitant, uncomfortable intestinal symptoms of the common cold.

Example 7

A syrup is prepared, as in Example 1, containing per teaspoonful, 7.25 mg. of 2-(diethylamino-ethoxy) ethyl phenyl-cyclopentyl-1-carboxylate citrate and 0.5 mg. of homatropine methylbromide.

When administered to one suffering from the symptoms of the common cold, the irritating cough which accompanies this condition is suppressed, the "tightness of the chest," which is produced by the antitussive drug, is relieved, and the person does not suffer from constipation.

Example 8

A tablet is prepared in accordance with the instructions of Example 2, except that the non-narcotic antitussive in this preparation is 2-(diethylamino-ethoxy) ethyl phenyl-cyclopentyl-1-carboxylate citrate (7.25 mg. per tablet), and the antispasmodic which relieves the side reactions of the antitussive, is the dipropyl acetyl ester citrate of tropine. This is included in the granulation in such a quantity that each tablet contains 2 mg. of antispasmodic.

The effects produced are similar to those described for the previous examples.

Example 9

A tablet is prepared in accordance with the instructions of Example 2, except that the non-narcotic antitussive is included in the granulation in such quantities that each tablet contains 25 mg. of 2-(diethylamino-ethoxy) ethyl phenyl-cyclopentyl-1-carboxylate citrate, and the spasmytic compound is 5 mg. of diethyl acetyl tropinium methylbromide per tablet.

When administered to a person suffering from cough produced by a cold or upper-respiratory infection, this effectively suppresses the cough and permits symptomatic relief of the chest symptoms, simultaneously relieving the intestinal spasm which commonly accompanies the use of the antitussive.

The dipropyl acetyl tropinium methylbromide and the dipropyl acetyl ester citrate of tropine are illustrative of a group of synthetic esters of tropine, its salts and quaternary ammonium salts which are described in the pending patent application of Nathan Weiner and Samuel M. Gordon, Serial No. 669,707, filed July 3, 1957, now U.S. Patent No. 2,962,499. The compounds in said pending application have the general formula, in quaternized form:

wherein:

R₁ and R₃ are alkyl radicals having 1 to 4 carbon atoms,

R₂ and R₄ designate hydrogen or alkyl radicals having 1 to 4 carbon atoms

R₅ designates hydrogen, alkyl, lower aralkyl, e.g., benzyl, substituted benzyl, phenethyl and substituted phenethyl radicals, and

X⁻ designates the anion of any suitable, or physiologically or pharmaceutically acceptable acid.

The improved compositions of this invention, it will be noted, are basically combinations of an antitussive, preferably a non-addictive one, and a non-addictive antispasmodic which is a synthetic ester of tropine or a salt thereof, or a quaternary ammonium salt thereof.

In the combination, the proportions of the spasmytic-to-antitussive can vary from 1:1 to 1:20.

It will be understood that the foregoing description of the invention and the examples set forth are merely illustrative of the principles thereof. Accordingly, the appended claims are to be construed as defining the invention within the full spirit and scope thereof.

I claim:

1. A composition comprising an antitussive and a spasmytic, wherein the antitussive is a member of the group consisting of dextro-3-methoxy-N-methyl morphinan hydrobromide, noscapine, and 2-(diethylamino-ethoxy) ethyl phenyl-cyclopentyl-1-carboxylate citrate.

2. A composition in accordance with claim 1 wherein the spasmytic is a member of the group consisting of synthetic esters of tropine, its salts and quaternary ammonium salts.

3. A composition in accordance with claim 1 wherein the antitussive is 2-(diethylamino-ethoxy) ethyl phenyl-cyclopentyl-1-carboxylate citrate.

4. A composition comprising 5-15 parts of 2-(diethylamino-ethoxy)ethyl phenyl-cyclopentyl-1-carboxylate citrate and 1-2 parts of homatropine methylbromide.

5. A composition comprising 10-20 parts of dextro-3-methoxy-N-methyl morphinan hydrobromide, and 1-3 parts of homatropine methylbromide.

6. A composition comprising 15-25 parts of dextro-3-methoxy-N-methyl morphinan hydrobromide and 3-5 parts of dipropyl acetyl tropinium methylbromide.

7. A composition comprising 10-15 parts of noscapine and 1-3 parts of homatropine methylbromide.

8. A solid composition comprising 10-20 parts of noscapine and 2-10 parts of dipropyl acetyl tropinium methylbromide.

9. A liquid composition comprising 10-20 parts of noscapine and 2-10 parts of dipropyl acetyl tropinium methylbromide.

10. A solid composition comprising 20-30 parts of 2-(diethylamino-ethoxy) ethyl phenyl-cyclopentyl-1-carboxylate citrate and 1-4 parts of homatropine methylbromide.

11. A liquid composition comprising 20-30 parts of 2-(diethylamino-ethoxy) ethyl phenyl-cyclopentyl-1-carboxylate citrate and 1-4 parts of homatropine methylbromide.

12. A composition comprising 10-20 parts of 2-(diethylamino-ethoxy) ethyl phenyl-cyclopentyl-1-carboxylate citrate and 3-10 parts of dipropyl acetyl ester citrate of tropine.

13. A composition comprising 20-30 parts of 2-(diethylamino-ethoxy) ethyl phenyl-cyclopentyl carboxylate citrate and 3-10 parts of dipropyl acetyl tropinium methylbromide.
